The ornamental design for a wireless dock, as shown and described.

DESCRIPTION

FIG. 1 is a front view of a wireless dock;

FIG. 2 is a back view of the wireless dock from FIG. 1; FIG. 3 is a left view of the wireless dock from FIG. 1; FIG. 4 is a right view of the wireless dock from FIG. 1; FIG. 5 is a top plan view of the wireless dock from FIG. 1; FIG. 6 is a bottom plan view of the wireless dock from FIG. 1;

FIG. 7 is a left perspective view of the wireless dock from FIG. 1, shown in an enlarged scale;

FIG. 8 is a right perspective view of the wireless dock from FIG. 1, shown in an enlarged scale; and,

FIG. 9 is a back perspective view of the wireless dock from FIG. 1, shown in an enlarged scale.

The broken line portions of FIGS. 2, 6, and 9 show unclaimed subject matter only and form no part of the claimed design. Additionally, line shading is meant to show contour of represented surfaces and not surface ornamentation.
